US00D688069S

(12) **United States Design Patent**
Henderson et al.

(10) **Patent No.:** US D688,069 S
(45) **Date of Patent:** ** Aug. 20, 2013

(54) **MATTRESS BED CUSHION**

(71) Applicants: **Randal Lee Henderson**, Zebulon, NC (US); **Stephen C. Kokenes**, Raleigh, NC (US); **Julian Thomas Young**, Zebulon, NC (US); **Mark Stearley**, Cary, NC (US); **Edouard Lauer**, Zebulon, NC (US)

(72) Inventors: **Randal Lee Henderson**, Zebulon, NC (US); **Stephen C. Kokenes**, Raleigh, NC (US); **Julian Thomas Young**, Zebulon, NC (US); **Mark Stearley**, Cary, NC (US); **Edouard Lauer**, Zebulon, NC (US)

(73) Assignee: **Noel Group LLC**, Zebulon, NC (US)

(**) Term: **14 Years**

(21) Appl. No.: **29/436,786**

(22) Filed: **Nov. 9, 2012**

Related U.S. Application Data

(62) Division of application No. 13/458,239, filed on Apr. 27, 2012, which is a division of application No. 13/630,435, filed on Sep. 28, 2012.
